UNITED STATES PATENT OFFICE.

GEORGE W. DREW, OF WASHINGTON, DISTRICT OF COLUMBIA.

DESIGN FOR A WATER-GAGE COLUMN.

SPECIFICATION forming part of Design No. 17,940, dated December 13, 1887.

Application filed November 3, 1887. Serial No. 254,228. Term of patent 3½ years.

To all whom it may concern:

Be it known that I, GEORGE W. DREW, a citizen of the United States, residing at Washington, in the District of Columbia, have invented and produced a new and original Design for Water-Gage Columns for Steam-Boilers, of which the following is a specification, reference being had to the accompanying drawings, in which—

10 Figure 1 is an elevation showing my newly-designed water-gage column. Fig. 2 is a vertical section taken on the line $x-x$ of Fig. 1, and Fig. 3 a horizontal section on line $y-y$ of Fig. 1.

15 Referring to said drawings, A represents the water-gage column, hexagonal in cross-section. B is the water-gage.

The top and base of the column are provided with similarly-formed enlarged top and base 20 portions C C, of the construction shown, having the heads D D substantially in the shape shown, the front or principal panel of the enlarged head and base portions being ornamented with a raised pyramidal figure, E, having substantially concave faces. At the center of the col-

umn is an enlarged portion, F, the front or principal panel of the same being ornamented by a raised circular figure, G, located in its center, and a raised star, G', on said circular figure. At each corner of this panel are raised 30 hemispherical knobs a , the upper and lower front panels, A' A'', of the column being ornamented by a representation of links, H, connected to form chain-work, the links being preferably rectangular in form. 35

I claim—

The design for a water-gage column for steam-boilers, consisting of the column A, provided with the enlarged top and base portions, C C, ornamented with the pyramidal figures 40 E E and heads D D, the central enlarged portion, F, ornamented with the raised circular figure G and raised star G', and the front or principal panels, A' A'', ornamented with the figure H, representing chain-work, substantially as shown and described. 45

GEORGE W. DREW.
